UNITED STATES PATENT OFFICE

HARVEY M. OLSTEAD, OF DENVER, COLORADO

PORTABLE THREADING DEVICE

Application filed May 24, 1930. Serial No. 455,317.

This invention relates to an attachment for portable electric drills so as to adapt them for threading pipe or other threading purposes. The principal object of the invention is to provide a simple and efficient attachment which can be quickly and easily applied to or detached from a portable electric drill so that the drill motor can be employed for rotating the threading die.

10 Another object of the invention is to so construct the device that dies of various sizes, threads, etc., can be quickly and easily interchanged.

15 Other objects and advantages reside in the detail construction of the invention, which is designed for simplicity, economy, and efficiency. These will become more apparent from the following description.

20 In the following detailed description of the invention reference is had to the accompanying drawing which forms a part hereof. Like numerals refer to like parts in all views of the drawing and throughout the description.

25 In the drawing:

Fig. 1 is a side elevation of the invention applied to a portable electric drill. In this view the gear box cover plate has been partially broken away to show the interior construction.

30 Fig. 2 is a plane view of the complete device of Fig. 1.

Fig. 3 is an enlarged vertical section through the gear box, taken on the line 3—3, Fig. 1.

Fig. 4 is a detail view of what might be termed the adapter for connecting the mechanism of this invention with the drill chuck.

40 In the drawing the motor of a typical portable electric drill has been illustrated at 10 with its feed cable at 11, gear casing at 12, and drill chuck at 13. The drill is preferably of the type having a reversible electric motor provided with a manually operated reversing switch such as indicated at 14.

45 The invention comprises a gear box 15 covered by means of a cover plate 16 secured thereon with suitable attachment screws 17. The gear box 15 encloses a worm gear 18 in mesh with a worm 19. The worm gear 18 is

formed with a hollow trunnion 20 which extends through the back of the gear box 15 and the cover plate 16 so as to form journals or bearings for the worm gear. The worm 19 is keyed on a worm shaft 21 which extends through one side of the gear box terminating in a clutch member 22. The other extremity of the worm shaft 21 is preferably carried in a bearing on a removable cap 23.

55 The entire gear box is secured to the extremities of a U-shaped frame member 24, which extends rearwardly to form a cradle for the drill motor 10, terminating in a reduced or handle portion 25. The drill motor 10 is secured in place in the cradle formed by the frame member 24 by means of a clamping band 26, the extremities of which may be drawn together by means of a clamp bolt 27 to cause the band to tightly grip the drill motor 10. The tongue of the gear box is absorbed in angle braces 31 which extend between the box and the frame member 24.

60 The power is transmitted through the medium of an adaptor illustrated in detail in Fig. 4. The adaptor comprises a stem 28 of a size to be conveniently placed into and clamped by the drill chuck 13, similarly to the manner of clamping a drill in the chuck. The stem 28 terminates in a head 29 provided with a plurality of sector-shaped teeth 30. The teeth 30 pass into the spaces between the teeth of a co-acting clutch member 22 of similar construction to the head 29. The teeth 30 are so formed that there will be a slight amount of play at this point so that 70 the members 22 and 29 not only form a tooth clutch but also a universal joint, to accommodate any misalignment in the positioning of the motor 10.

75 The thread cutting die may be secured to the worm gear 18 in any desired manner. A very satisfactory method of accomplishing this is illustrated in the drawing, in which a cylindrical stock 32 passes completely through the trunnion 20 of the gear 18. The 80 stock 32 carries a square die socket 33 at its one extremity closed by means of a pivoted cover plate 34. The die socket 33 is adapted to receive a square die 35 of the type known as a "Reed" die. The cover plate 34 is piv- 85

90 95 100

oted on a pivot screw 36 at one corner and secured by means of a wing nut 37 at the opposite corner. By loosening the wing nut 37 the cover plate 34 may be rotated about the 5 pivot screw 36 so as to allow the die 35 to be easily removed from the socket 33.

The stock 32 may be secured to the worm gear 18 in any desired manner such as by 10 threading a set screw 38 into the joint between the die and gear as illustrated. A reducing sleeve 39 may be secured in the opposite end of the die 38 by means of a set screw 40 when it is desired to thread smaller pipe than the interior diameter of the die.

15 In use, the stock is slipped over the extremity of a pipe or rod and the motor started in the "forward" direction. When the desired length of thread has been cut, the reversing switch 14 is operated to reverse the 20 motor and back the die from the thread.

When the threading operations have been completed the motor 10 can be quickly released by loosening the clamp screw 27 so that the drill may be used for other 25 purposes.

While a specific form of the improvement has been described and illustrated herein, it is desired to be understood that the same may be varied within the scope of the appended 30 claims without departing from the spirit of the invention.

Having thus described the invention, what is claimed and desired secured by Letters Patent is:

35 1. A threading attachment for portable electric drills comprising; a gear box; a worm gear journaled in said gear box; a pipe threading die operatively connected to said worm gear and positioned on the exterior of said gear box; a worm shaft extending laterally of said worm gear and projecting from said gear box; means for connecting said worm shaft to the shaft of a portable drill; a U-shaped frame secured 40 at its extremities to opposite sides of said gear box and extending rearwardly along each side of said portable drill to align the latter with said worm; and a clamping band arranged to hold said portable drill in said 45 U-shaped frame member.

50 2. A threading attachment for portable electric drills comprising: a gear box; a worm gear journaled in said gear box; a pipe threading die operatively connected to 55 said worm gear and positioned on the exterior of said gear box; a worm shaft extending laterally of said worm gear and projecting from said gear box; means for connecting said worm shaft to the shaft of a portable drill; a U-shaped frame secured at its extremities to opposite sides of said gear box and extending rearwardly along each side of said portable drill to align the latter with said worm; a clamping band 60 arranged to hold said portable drill in said 65

U-shaped frame member; and an angle brace extending from each side of said U-shaped frame to opposite sides of said gear box to rigidly maintain said worm in alignment with said portable drill.

70 3. A threading attachment for portable electric drills comprising: a gear box; a worm gear journaled in said gear box; a pipe threading die operatively connected to 75 said worm gear and positioned on the exterior of said gear box; a worm shaft extending laterally of said worm gear and projecting from said gear box; means for connecting said worm shaft to the shaft of a portable drill; a U-shaped frame secured 80 at its extremities to opposite sides of said gear box and extending rearwardly along each side of said portable drill to align the latter with said worm; a clamping band arranged to hold said portable drill in said 85 U-shaped frame member; and a handle formed on said U-shaped frame at the rear of said portable drill.

90 4. A threading attachment for portable electric drills comprising; a gear box; a worm gear journaled in said gear box; a pipe threading die operatively connected to 95 said worm gear and positioned on the exterior of said gear box; a worm shaft extending laterally of said worm gear and projecting from said gear box; means for connecting said worm shaft to the shaft of a portable drill; a U-shaped frame secured 100 at its extremities to opposite sides of said gear box and extending rearwardly along each side of said portable drill to align the latter with said worm; a clamping band arranged to hold said portable drill in said 105 U-shaped frame member; a handle formed on said U-shaped frame at the rear of said portable drill, said handle comprising a narrowed rearwardly projecting portion of said frame.

110 In testimony whereof I affix my signature.

115 HARVEY M. OLMSTEAD.
